UNITED STATES PATENT OFFICE.

LOUIS M. MARBLE, OF WASHINGTON, DISTRICT OF COLUMBIA, ASSIGNOR TO
THE BELMAR MANUFACTURING COMPANY, OF PENNSYLVANIA.

GARMENT-HOLDER.

SPECIFICATION forming part of Letters Patent No. 666,608, dated January 22, 1901.

Application filed December 1, 1900. Serial No. 38,321. (No model.)

To all whom it may concern:

Be it known that I, LOUIS M. MARBLE, a citizen of the United States, residing at Washington, in the District of Columbia, have invented new and useful Improvements in Garment-Holders; and I do hereby declare the following to be a full, clear, and exact description of the invention, such as will enable others skilled in the art to which it appertains to make and use the same.

One of the chief defects of the garment-holders now in most general use on the market is the tendency of the ends of the frames to crack and tear the lining of garments placed thereon, to form "pockets" where the ends strike the fabric, and even in some cases to work a hole in the fabric. There is also a great lack in the efficiency of the holders due to the fact that they are all made from the same pattern and that no means are provided whereby they may adjust themselves to differing sizes of garments. With these facts in mind, and knowing that it is as unreasonable to expect a given garment-holder to fit all sizes and conditions of garments as it is for one garment to fit all sizes and conditions of persons, I aim to provide a garment-holder which can be easily and quickly adjusted to different garments and which will also not mar or tear the most delicate fabric placed thereon.

In accomplishing the object of my invention I make use of elasticity as a means for varying and adjusting the curve and conformation of the frame on which the garments rest by constructing the frame of a spring and providing means for adjusting the spread or curve of the same. As in coats and waists the difference in size is manifested, so far as the garment-holder is concerned, in a different slope and breadth of the shoulder-seam, so in skirts the difference in construction with which the garment-holder has to do is a difference of curve caused by varying waist and hip measures. In both instances variation in the spread of the arms of the garment-holder will cause such an adjustment of the bend of the frame as will accommodate the holder to different garments, while the position in which the ends of the spring-frame are held by the means used to hold the frame in the desired

curve acts in practice, on account of the lines of garments, to prevent the ends of the spring-frame from injuring or marring in the slightest the most delicate lining. I preferably use wood as the material from which to construct the spring-frame, as it lends itself to graceful curving on its upper face without getting so strong in its spring action as to be hard to adjust. Smoothly-finished wood has also no tendency to cut fabric or to form seams or lines in the same.

My holder is adapted to serve both as a coat and waist holder and as a skirt-holder, the frame in the latter case being made longer, so as to permit of being bent into a semicircular shape. When used as a skirt-holder, I also provide a band, secured preferably to the center of the spring-frame, which can be looped around the skirt-band when hooked together at the placket-opening and then caught back on itself, thus supporting the heavy folds at the back of the skirt and preventing the skirt from sagging.

A further object of my invention is to provide a detachable supporting-hook on account of the conveniences arising therefrom for packing and manufacturing purposes.

My invention is fully illustrated in the drawings which accompany and form a part of this specification, in which the same reference-letters refer to the same or corresponding parts, and in which—

Figure 1 is a face view of my holder used as a coat-holder. Fig. 2 is a similar view of the holder bent so as to serve as a skirt-holder. Fig. 3 is a detail view of one of the ends of the holder. Fig. 4 is a detail section showing the method of attachment of the supporting-hook as modified from that shown in the other views, so as to be detachable.

Referring to the drawings, A represents the spring-frame; B, the supporting-hook; C, the adjustment means used to control the spread of the arms of the frame A, and D the flexible band adapted to loop around the skirt-band and support the heavy folds at the back of the skirt.

The elastic frame A may be of any desired material; but I preferably make it of some springy wood—such as oak, ash, or hickory—on account of cheapness of manufacture and

because of the fact that wood, when rounded and free from sharp edges, has no tendency to mar or wear any fabric resting thereon. The length and shape of the normal curve given to the frame depends upon the use to which the holder is to be put. Both coat and skirt holders are illustrated in the drawings.

It will be noted that the ends of the frame are slightly thinner than the central portion.

- 10 This is to give the spring action to the frame when bent and to render the frame adjustable as regards the distance between the ends of the same. It also causes the frame, when bent into operative position, to bend with its center portion only slightly curved and its ends very much curved. The form thus obtained is very useful in rendering my holder capable of acting as a skirt-holder as well as a coat and waist holder.
- 15 20 To adjust the frame A to accommodate different sizes and shapes of garments, the adjustment device C is employed. This device also acts as a means to hold the spring-frame in place. It consists of chains c, one for each end of the frame, which are introduced in the slots a, formed in the ends of the frame A, and in the link c', which serves to connect the ends of the chains. Variation in the spread of the arms of the frame A is produced 25 30 by varying the link of the chain in which the hook c² of the link c' is caught. It is of course evident that many other forms of construction may be used in place of that here described, and I do not limit myself to the 35 construction shown.

The supporting - hook B may be formed either with a recess to receive the collar of a coat or in the straight form shown. It is made of twisted wire, so as to be formed with 40 a bifurcated or forked lower end b. Connection of the hook B to the frame A is effected through the block E, which is formed, as shown, with a central opening e, through which the body or main portion of the hook 45 B passes, and with smaller holes e', (which preferably do not extend through the block,) into which the forked ends b of the hook B enter. The block E may be immovably attached to the frame A by being glued to the 50 same or in other ways; but for some purposes I prefer to make it removable. One removable construction is shown in Fig. 4. Pins e² are secured to the lower surface of the block E (which is of necessity curved to correspond with the conformation of the upper 55 face of the frame A) and pass through holes a⁵, formed in the frame A, nuts e⁴ screwing on the screw-threaded projecting ends e³ of the pins e² and making secure the connection 60 between the block and the frame. The advantage in making the supporting - hook removable is that it permits economy of much space in packing, and thus cheapens transportation.

65 65 When my holder is used as a skirt-holder, as shown in Fig. 2, a flexible loop D is employed to catch around the skirt-band of the

skirt where the band is hooked together at the placket-opening. In the construction shown the loop D is a broad open-linked 70 chain; but it may as well be made of tape or knotted cord. In operation the downwardly-hanging end of the loop D is passed through the placket-opening under the hooked skirt-band and then drawn upward until all sagging is removed from the hang of the heavy folds at the back of the shirt, when it is caught into one of the open links, or the hook and eye of the waistband may when fastened be caught through one of the open links. 80

Many modifications and changes in form and construction may be introduced into my holder without departing from the spirit and scope of my invention, and I do not limit myself to the form and construction shown; but 85

What I claim as new, and desire to secure by Letters Patent, is—

1. In a garment-holder, a frame for supporting the garment or garments consisting of a bow-spring having both ends tapering in 90 thickness from its center, whereby the spring is adapted to bend with its central portion only slightly curved and its ends very much curved, and means for holding the spring in operative position, substantially as described. 95

2. In a garment-holder, the combination with a spring frame or support for the garment or garments, of an adjustable link-and-chain connection between the two ends of said spring-frame, substantially as described. 100

3. In a garment-holder, the combination with a frame or support having curved sides upon which the waistband of a skirt can rest, of a flexible band supported by said frame, and means for enabling the end of said band 105 to be caught back on said band, whereby the lower end of the band may be looped through some portion of the skirt and then caught back on itself, thus preventing sagging of the skirt, substantially as described. 110

4. In a garment-holder, the combination with a frame or support having curved sides upon which the waistband of a skirt can rest, of a chain with open links secured to said frame and adapted to support the heavy folds 115 of a skirt, substantially as described.

5. In a garment-holder, the combination with a frame for the garment or garments, of a suspension-hook, a retaining-block adapted to be secured to said frame, and means for 120 holding said suspension-hook in position between said block and said frame, substantially as described.

6. In a garment-holder, the combination with a frame for the garment or garments, of a suspension-hook, and a retaining - block, adapted to be secured to said frame, and formed with means for holding said suspension-hook in position between said block and said frame, substantially as described. 125

7. In a garment-holder, the combination with a frame for the garment or garments, of a suspension-hook, and a retaining - block formed with recesses adapted to receive a part 130

of said suspension-hook, substantially as described.

8. In a garment-holder, the combination with a frame for the garment or garments, of a suspension-hook formed with an angled lower end, a retaining-block, and means for holding said suspension-hook in position between said block and said frame, substantially as described.

9. In a garment-holder, the combination with a frame for the garment or garments, of

a suspension-hook formed with an angled end, and a retaining-block formed with angled recesses for holding said suspension-hook in position, substantially as described.

15

In testimony whereof I affix my signature in the presence of two witnesses.

LOUIS M. MARBLE.
